[57] **CLAIM**

The ornamental design for a bulk container frame, as shown and described.

DESCRIPTION

FIG. 1 is a front perspective view of a bulk container frame of our new design, shown holding a bottle in dashed lines; FIG. 2 is a front elevational view of the bulk container of FIG. 1 without the bottle; FIG. 3 is a right side elevational view of the bulk container of FIG. 1 without the bottle; FIG. 4 is a top plan view of the bulk container of FIG. 1 without the bottle; FIG. 5 is a rear elevational view of the bulk container of FIG. 1 without the bottle; FIG. 6 is a front perspective view of an alternate bulk container frame of our new design, shown holding a bottle in dashed lines; FIG. 7 is a front elevational view of the bulk container of FIG. 6 without the bottle; FIG. 8 is a right side elevational view of the bulk container of FIG. 6 without the bottle; FIG. 9 is a top plan view of the bulk container of FIG. 6 without the bottle; and, FIG. 10 is a rear elevational view of the bulk container of FIG. 6 without the bottle. The broken line showing of the bottle in FIGS. 1 and 6 is for illustrative purposes only and forms no part of the claimed design.
